UNITED STATES PATENT OFFICE.

FRANK HORAK, OF VALPARAISO, INDIANA.

PADLOCK.

Application filed August 29, 1925. Serial No. 53,249.

My invention relates to improvements in padlocks and it more especially consists of the features pointed out in the annexed claims.

5 The purpose of my invention is to provide a padlock in which all the advantages of a variably notched flat key are appropriated without unduly increasing the size of the padlock; that uses an oscillating or 10 rocking key carrier; that combines with the key carrier a variably notched locking plate; that utilizes a sliding hasp which, in its unlocked position, may be rotated on the axis of one of its members; and that 15 is simple in construction and very effective in practice.

With these and other ends in view, I illustrate in the accompanying drawing such instances of adaptation as will show the 20 broad underlying features of my invention, without limiting myself to the specific details shown thereon or described herein.

Figure 1 is an elevation in section on line 1—1 of Fig. 2.

25 Fig. 2 is an elevation in section approximately on line 2—2 of Fig. 1.

Fig. 3 is a plan view in section on line 3—3 of Fig. 1.

30 Fig. 4 is a view similar to Fig. 1 showing a key in position to unlock the hasp.

Fig. 5 is a side elevation partly in section.

Fig. 6 is a detached elevation of the locking end of the hasp.

35 Fig. 7 is a perspective view of the locking plate.

In practically carrying out my invention, I may use any desired form or shape of casing 1. Whatever the extent or shape of the casing is, it is supplied in its front edge with 40 a recess 21 to receive the short end 3 of the hasp 2. Another opening 8 is formed from the same face and it extends almost through the casing 1 as shown in the figures of the drawing. This hole accommodates the long 45 end 4 of the hasp 2. Another opening 22 is formed in the casing 1 from the lower edge of the casing. This opening receives the key carrier 18.

In addition to the larger openings 8, 50 21, and 22 a number of smaller openings are formed in the side edges of the casing. In the right hand edge a small hole is made for the retaining pin 10 which serves to prevent the complete withdrawal

of the hasp 2 when it is in its unlocked 55 position, by reason of the fact that the front end of this pin engages a flattened face 9 of the locking end 4 of the hasp 2. In the left hand edge a series of four 60 small holes are shown in which key co-operating limit pins slide. The pins 24 are commonly called drivers. They are pressed forward by springs 25 and the openings in which the pins 24 slide are closed by 65 plugs 26. A companion group of key pins 27 have radial sliding movement in the key carrier 18. This key carrier has an endwise key groove or slot 19. The function of the pins 27 and drivers 24 in relation to the notches of the key 23 are well 70 known and need not be further described.

The key carrier 18 is held in place by a locking plate 11 which has sliding movement in the transverse slot 15. A notch 16 is formed in the under edge of the locking plate 11. A key engaging notch 13 is formed at the deepest portion of the notch 16. The other edge 14 of the notch 16 engages the annular groove 20 formed in the key carrier, while the plate 11 is in 80 its locked position, as shown in Fig. 3; and the forward edge of the notch 16 also slides in the groove 20 when the plate 11 is in its unlocked position. This plate 11 has a rearwardly extending pin 12 which enters 85 an opening of the casing in which a spring 28 is placed. A plug similar to plugs 26 serves to hold the spring 28 in its opening.

The locking plate 11 is held in place by a cover 17, as shown in Figs. 2, 3, and 5. The long end 4 of the hasp 2 terminates in the end 6 formed beyond the locking groove 5. It is constantly under the pressure produced by the hasp spring 7, which spring serves to push the short end 3 of the hasp 2 out of the opening 21 to unlock the lock whenever the key 23 is turned to the left so that its upper edge will engage the notch 13 and thus pull the locking plate 11 out of the groove 5. As soon as the key is removed, or even before if the spring 28 is strong enough, the plate 11 is pressed against the head 6 ready to move into the groove 5 when the hasp 2 is pressed down so that its short end 3 is seated in the opening 21, which effectually locks the hasp in position until the key is again turned to the left to remove the locking plate 11 from the groove 5. When 90 95 100 105

the hasp 2 is pushed endwise by the spring 7 until the short end 3 is removed from the opening 21, it can be rotated on the axis of the long end 4 so as to attach the hasp wherever desired.

It is of course understood that in addition to the notches formed on the edge of the keys 23 they may also have differentiating grooves formed on one or both faces lengthwise of the keys, in order to multiply the permutation of the key notches which, in the case of four driving pins, produces ten thousand possible key changes.

It will be seen that my padlock is self-contained and simple in operation and construction.

What I claim is:

1. In padlocks, a casing having a plurality of openings formed in one edge thereof, a hasp slideable in a plurality of such openings and rotatable in one of them, a key carrier positioned in an opening formed in the opposite edge of the casing said carrier having a lengthwise key receiving groove formed therein, an annular groove formed in the long end of the hasp, an annular groove in the key carrier, a notched locking plate movable transversely in the annular groove of the key carrier and adapted to simultaneously engage the annular groove of the hasp, and suitable springs for subjecting the hasp and the locking plate to pressure.

2. In padlocks, a casing, a hasp slideable and rotatable in the casing having an annular groove formed in its one end, a key carrier having an annular groove formed thereon, a locking plate adapted to simultaneously engage the hasp and the key carrier, a spring for pressing the hasp in one direction, a spring for pressing the locking plate against the hasp, and means for mov-

ing the carrier on its axis to thereby shift the locking plate and release the hasp.

3. In padlocks, a casing, a key carrier in the casing having a lengthwise groove formed therein to receive a key slideable in the groove, an annular groove formed on the carrier positioned between its ends, a notched locking plate transversely movable in the annular groove of the carrier adapted to hold the key carrier positioned endwise in the casing, and cooperating limiting means between the casing the key carrier and the key for freeing the carrier from the casing in order that it can be rotated on its axis at the same time that the locking plate is moved transversely of the carrier.

4. In padlocks, a locking plate having a variable depth and width notch formed in its one side edge and a recess in one end, a spring engaging pin projecting from the other end of the plate, a suitable casing having a recess to receive the plate, a spring for exerting pressure against the pin, a hasp movable in the casing to cooperate with the recess, and a cover secured to the casing for holding the locking plate and associated parts in assembled relation.

5. In padlocks, a casing, a hasp slideable and rotatable in the casing said hasp having an annular groove formed thereon, a key carrier, an annular groove formed in the carrier, locking means for simultaneously engaging the hasp and the key carrier, means for pressing the hasp endwise, means for engaging the locking means with the groove of the hasp, and means for moving the carrier on its axis to thereby shift the locking means out of engagement with the hasp to free it for endwise movement.

In testimony whereof I affix my signature.

FRANK HORAK.
